Primary Examiner — Catherine S Posthauer*Assistant Examiner* — Christine Marie Achen Zimmerman
(74) *Attorney, Agent, or Firm* — Sang Young Han(57) **CLAIM**

The ornamental design for a knife block and cutting board set, as shown and described.

DESCRIPTION

FIG. 1 is a front perspective view of a knife block and cutting board set, showing my new design;

FIG. 2 is a bottom perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top view thereof;

FIG. 8 is a bottom view thereof; and,

FIG. 9 is a perspective view of the knife block and cutting board set in a separated configuration.

The broken lines in the drawings illustrate the portions of the knife block and cutting board set, which form no part of the claimed design.

1 Claim, 9 Drawing Sheets(56)
